UNITED STATES PATENT OFFICE.

THOMAS J. CLINTON, OF DETROIT, MICHIGAN.

REFRIGERATOR.

1,404,191.

Specification of Letters Patent. Patented Jan. 24, 1922.

Application filed November 11, 1918. Serial No. 261,969.

To all whom it may concern:

Be it known that I, THOMAS J. CLINTON, a citizen of the United States, residing at Detroit, county of Wayne, State of Michigan, have invented a certain new and useful Improvement in Refrigerators, and declare the following to be a full, clear, and exact description of the same, such as will enable others skilled in the art to which it pertains to make and use the same, reference being had to the accompanying drawings, which form a part of this specification.

This invention relates to improvements in refrigerators and is a continuation of my application Serial No. 162,424, filed April 6, 1917, as to all common subject matter. The primary object of this invention is to provide a refrigerator of a construction of such character that the carbon dioxide usually given off by food in a storage compartment is eliminated and replaced by fresh air of a temperature below that of atmospheric air, and further to provide a construction in which the accumulation of moisture within the storage compartment is reduced to a minimum and produce a more rapid circulation of cooled air within the compartment.

In practice I have found that the decay of the fruit and deterioration of meat and similar perishable products is caused largely by the presence of gas arising from the product (principally carbon dioxide) and moisture which forms a slime permeating the product and hastening its ripening or decay. The principal object of this invention is a construction by means of which such gases and moisture may pass from the storage compartment and fresh previously cooled air introduced into the circulating medium without increasing the temperature of the storage compartment to a detrimental degree. These and other objects and the several novel features of the invention are hereinafter more fully described and claimed and shown in preferred form in the accompanying drawings in which—

Fig. 1 is a vertical section of a refrigerator embodying my invention.

Fig. 2 is a vertical section taken on line $x-x$ of Fig. 1.

Fig. 3 is a horizontal section taken on line $y-y$ of Fig. 1.

As will be readily understood, the general type of construction herein illustrated may be used with any type of refrigerator

and the description of the storage compartment, while specific to the one shown in detail in the drawings will apply generally to the various type of refrigerators whether cooled by natural ice or by artificial systems and to either stationary or movable refrigerators. The refrigerator indicated is of an ordinary type having a storage compartment 1 and an ice compartment 2 formed at one side thereof which is in the nature of a bunker having an apertured bottom 3 and a drain pipe 4. This particular means for icing, however, is not material and is shown only to illustrate the principles of operation. In whatever type of refrigerator the invention is to be applied I provide what I have termed the tempering compartment 4 adjacent the ice compartment, being separated therefrom only by the wall 5 as indicated. This tempering compartment 4 is closed or sealed except as to an outlet 6 into the storage compartment at about the top of the ice compartment and an opening formed by the tube 7 through the exterior wall of the refrigerator to atmosphere. This latter tube 7 should be positioned out of alignment with the aperture 6 in the wall 5 and preferably above the aperture as is indicated in Fig. 1. A false ceiling 8 is also provided in the refrigerator forming a flue 9 between the false ceiling 8 and top of the refrigerator preferably extending entirely across the refrigerator as will be understood from Fig. 3 being supported by longitudinal strips 10 in staggered relation as shown. This false ceiling 8 is provided with a slot 11 preferably extending entirely across the refrigerator near the end of the storage compartment and preferably opposite the ice chamber or remote from it, being preferably some little distance from the opposite wall for reasons as will hereinafter appear. In the construction here shown, an outlet tube 12 for the flue 9 is provided directly over the ice chamber at the side of the refrigerator opposite the inlet slot 11, and the supporting members 10 of the false ceiling terminate short of the said outlet end in order that gas flowing into the slot 11 at any point may pass out through the tube 12 eliminating dead air spaces in the said flue.

By reason of contact of the atmosphere of the storage compartment with the ice chamber wall and with the ice or refrigerating element, the atmosphere of the storage chamber will circulate substantially as indicated

by the arrows shown in Fig. 1, the flow being downward adjacent the ice compartment and thence across the bottom of the storage compartment to the opposite side 5 and thence upward. The slot 11 is located at a point where the upwardly ascending current would naturally strike the ceiling and provides a ready outlet for the gases that are forced to this point. The slot is 10 located some little distance forward of the chamber wall and clear of the dead air space formed at the corner of the chamber.

Carbon dioxide, although being heavier than air, tends to fall toward the bottom of the 15 compartment but, due to the cooling effect of the ice chamber and the tendency of the atmosphere adjacent thereto to flow downward, such gases are forced to circulate with the warmer and lighter gases and thus are 20 brought to a point where they may pass off through the flue 9. This discharge of gases and lighter constituents and moisture is accomplished as fresh air may be drawn into the compartment through the aperture 6 25 and tube 7 so there is no tendency to produce diminished pressure within the compartment. By arranging the tube 7 and aperture 6 in the manner heretofore stated, atmospheric air may flow into the chamber 30 4 through the tube 7 contacting the inner wall 5 of the tempering chamber which is naturally cold by reason of its being contiguous to the cooling medium. The air is thus cooled as it enters the chamber 4 and 35 tends to fall in the said chamber whenever any diminished pressure occurs therein which would be by reason of air flowing through the apertures 6 to replace the gases passing through the outlet 11. The air passing 40 into the circulating medium in the storage compartment is thus previously cooled tending to condense the moisture therein and in passing across the top of the ice as shown is further cooled and thus enters the 45 storage compartment proper practically dry and in condition to absorb moisture and heat from the stored product. The condensation passes out through the drain pipe 4. This warmer air of course tends to rise and pass 50 out through the flue and thus a natural circulation is induced far more rapid than in the closed type of refrigerator in which the atmosphere soon becomes dead by reason of its entire volume being nearly of the same 55 temperature.

The peculiar construction shown therefore 60 is productive of more rapid circulation, eliminates the warmer gases which become laden with moisture within the compartment, and the air flowing into the compartment has the moisture partially at least discharged therefrom prior to entering the storage compartment which is maintained practically free from moisture, and the gases are 65 discharged therefrom practically as rapidly

as produced by the stored product. By eliminating the moisture and the gases as stated, the tendency of deterioration is reduced to a minimum and as circulation is maintained at a maximum every part of the compartment is subjected to fresh cold air, and a refrigerator more highly efficient than the usual type is secured.

It is to be understood that the openings 6, 7 and 12 are not of very great capacity. The 75 apertures 6 and 7 are about three-eighths of an inch in diameter for an ordinary household refrigerator and the discharge tube 12 is somewhat larger in diameter, but these diameters may be varied somewhat and 80 naturally must be increased for refrigerators of much great capacity. The apertures are therefore insufficient to cause any rapid discharge of gas, the purpose being only to cause a sufficient discharge to take care of 85 accumulation of the gases in the compartment. The aperture tube 12 is made larger than the inlet so that the gases may have a free exit.

In refrigerators in use I have found that 90 meat for instance will become thoroughly dry after a period without becoming contaminated in any way, and that raspberries for instance, which in an ordinary refrigerator become covered with a mold, may remain for months in my improved refrigerator without any mold appearing, the only effect being a shrinkage in size. Also salt maintained for several weeks in this refrigerator remains perfectly dry even though adjacent the ice compartment indicating that the atmosphere of the compartment is practically free from moisture and the fact that meat and other articles do not decay or become putrid even after a long period of time 105 indicates that the gases arising from the product are completely discharged. Circulation of a substantially pure cold air is therefore accomplished by the construction described.

With other arrangements of ice compartment than is here shown, slightly different arrangement of the inlet and outlet openings must necessarily be provided, but the relative arrangement must be practically the same as here shown. The outlet 11 should be placed at a point where the ascending current of air may readily pass into the flue 9 and above the inlet 6 of the tempering chamber 4, and the inlet 6 should be positioned substantially in the relation to the ice compartment as is here shown.

Having thus briefly described my invention, its utility and mode of operation, what I claim is—

1. In a refrigerator, in combination, a casing forming a storage compartment, an ice chamber therewithin at one side of the storage compartment, an inlet to atmosphere opening into the storage compartment over 130

the top of the ice chamber, a flue for gases extending across the top of the storage compartment and open to the compartment at a distance from the ice chamber and through 5 the top of the refrigerator at a point remote from its inlet to the storage compartment.

2. In a refrigerator in combination, a casing forming a storage compartment, an 10 ice compartment therewithin at one side of the storage compartment, said ice compartment being open to the storage compartment at the top, a tempering chamber the inner wall of which forms a wall of the ice compartment, said tempering chamber having an opening into the storage compartment just above the ice compartment and also having an opening to atmosphere, a flue extending across the top of the refrigerator 15 20 above the ice compartment and having an opening into the storage chamber at a point remote from the ice compartment, said flue discharging to atmosphere at a point remote from the inlet.

25 3. In a refrigerator, a storage compartment, a cooling chamber at one end spaced from the wall of the storage compartment providing an air chamber between the cooling chamber and wall of the storage compartment, said air chamber having an opening to atmosphere through the wall of the storage compartment and having an opening leading into the storage chamber out of 30 alignment with the said opening to atmosphere, and a flue provided in the ceiling of 35

the compartment having an opening into the storage compartment at a point remote from the ice compartment and also provided with an opening discharging to atmosphere.

4. In a refrigerator, a storage compartment, a cooling medium compartment therewithin open to the storage compartment at the top, said cooling medium compartment being spaced from the wall of the storage compartment providing a tempering chamber, said tempering chamber having an opening in communication with atmosphere and an opening leading into the storage compartment, a shield extending across the upper side of the compartment open to atmosphere through the top of the refrigerator at one end and opening into the storage compartment near the opposite end. 40 45

5. In a refrigerator, a storage compartment, an ice chamber at one end spaced from the wall of the storage compartment and providing an air space closed to the storage compartment at the bottom and provided with an opening in the upper end over the ice compartment, a passageway in the outer casing out of alignment with the first named opening and providing an inlet to the said air space and an outlet passageway in the upper side of the storage compartment opening thereinto above the inlet. 50 55 60 65

In testimony whereof I sign this specification.

THOMAS J. CLINTON.
